LENS HOUSING FOR AN AUTOMOBILE LAMP

Herbert F. Weissinger, Franklin, Mich., assignor to Chrysler Corporation, Highland Park, Mich., a corporation of Delaware

Application September 2, 1955, Serial No. 37,767

Term of patent 7 years

(Cl. D48—32)

Fig. 1 is a front elevational view of a lens housing for an automobile lamp showing my new design;

Fig. 2 is a side elevational view thereof;

Fig. 3 is a sectional view taken on the line 3—3 of Fig. 1;

Fig. 4 is a sectional view taken on the line 4—4 of Fig. 3; and

Fig. 5 is a sectional view taken on the line 5—5 of Fig. 2.

I claim:

The ornamental design for a lens housing for an automobile lamp, substantially as shown.
